UNITED STATES PATENT OFFICE.

GEORGE WALTHER, OF DAYTON, OHIO, ASSIGNOR TO THE DAYTON STEEL FOUNDRY COMPANY, OF DAYTON, OHIO, A CORPORATION OF OHIO.

WHEEL.

Application filed July 5, 1922. Serial No. 572,831.

To all whom it may concern:

Be it known that I, GEORGE WALTHER, a citizen of the United States, residing at Dayton, in the county of Montgomery and State of Ohio, have invented certain new and useful Improvements in Wheels, of which the following is a specification, reference being had therein to the accompanying drawing.

10 My invention relates to an apparatus for and a method of casting steel wheels, and in particular to cores therefor.

It is the object of my invention to provide a means for and method of producing rapidly on a quantity basis cores used for cast steel wheels.

It is an additional object to provide core plates, portions of which may be adjusted according to sizes, in order to accommodate 20 different types and sizes of hubs.

It is a further object of my invention to produce core plates which will enable the ready assemblage of the core halves, and their transportation as a unit to the place 25 where the cores are baked.

It is an additional object to provide a single core plate which will have a flat surface and will therefore have the minimum of difficulties in being machined when the core 30 plate warps due to the fact of heat thereon.

It is a further object to provide cores having a plurality of supporting arbors and positioning chaplets together with means detachable from the assembling core for supporting and transporting it.

Referring to the drawings:

Fig. 1 is a plan view of the completed core showing the arbors, chaplets and apparatus for supporting strings;

40 Fig. 2 is a section of one half of the core with arbor and chaplet in place;

Fig. 3 is a similar view of the one half of the core plate and core;

45 Fig. 4 is a section of the assembled core and core plates;

Fig. 5 is a section of an alternate form of core plate;

Fig. 6 is a section on the line 6—6 of 50 Fig. 1;

Fig. 7 is a section on the line 7—7 of Fig. 4;

Fig. 8 is a section through the core and the core plate shown in Fig. 5.

Fig. 9 is a plan view of the core plate shown in Fig. 5.

Referring to the drawings in detail, 1 is the hub portion of the core, 2 is the spoke portion and 3 is the rim portion. In the periphery of the core in the rim portion are the openings 4 through which cords or 55 strings are inserted for lifting and supporting the complete core. 5 is an arbor having the diverging outer ends 6 and the heads 7 adjacent the hub. The heads overlap and the outer ends 6 overlap to give 60 strength and stability to the core. In the form of my invention shown in Figures 2, 3 and 4 I employ a two piece core having a parting line. For the parts in making 65 this core I select one half of the core plate or one section thereof which consists of a spoke portion, a hub portion 10, a rim portion 11, and certain connecting members on the periphery of these plates. On the half of the core plate shown in Fig. 2 there is 70 mounted a hook 12 which engages with a ball 13 on the other half of the core plate seen in Fig. 3.

This engagement is made by the insertion 75 of hook 12 in the aperture 14. Cutaway portions 15 are provided in spoke portion 9 for the insertion of the chaplets 16.

In order to vary the sizes of the hubs I provide detachable blocks 17 which are retained in position by a plurality of lugs 18 85 which are mounted upon 10. By changing the sizes and configuration of the blocks, it is possible to vary the hub dimensions of the core without otherwise disturbing the core plates as the variations in the wheels 90 are principally found in the hub dimensions.

In assembling the core plates the plates are filled with the green sand, and afterward its chaplets are located, and its arbors are placed in position, whereupon the two halves are hooked together as described and are gradually brought together with the edges having the ball and hook on the ground. Upon the two halves being united the core 95 can then be baked and completely removed.

The movement of the completed core may be effected as desired by inserting strings or cords through the aperture 4, enabling the workmen to move the core as a unit to a position in its flask.

100 In case it is not desired to use core boxes a

core plate which is nearly flat may be employed, as seen in Figures 5, 8 and 9. A plate having a marginal band 19 is provided. Within 19 is a continuous cutaway portion 20 for the rim and 21 for the spokes and a hub portion 22 which is open. The moulded sand core is of one piece with a supporting arbor and has no parting line. It rests upon this core plate until it is completely baked. This type of core plate may be readily machined as it does not have any difficult places for grinding in order to make it true if it has warped.

It will be understood that I do not desire to be confined to this specific adaptation of my invention, but comprehend within it suitable modifications which may be necessary in adapting it to varying conditions.

Having thus fully described my invention, what I claim as new and desire to secure by Letters Patent, is:—

1. In an apparatus for making cores, a core plate for one half of the core, a second core plate for the other half of the core, separable means for pivotally connecting said core plates to one another whereby the halves of the cores may be joined together and be transported as a unit.

2. In an apparatus for making cores, a core plate for one half of the core, a second core plate for the other half of the core, means of pivotally connecting said core plates to one another, and removable means adjacent the hub portion of the cores for determining the configuration thereof, and means to retain in position said means whereby the halves of the cores may be joined together and be transported as a unit.

3. In an apparatus for forming cores, a core plate which forms one half of the core, said core plate having rim, spoke, and hub portions, a second similar half of a core plate, and separable means for pivotally uniting said plates whereby cores placed in each core plate may be brought together to form a single core.

4. In an apparatus for forming cores, a core plate which forms one half of the core, said core plate having rim, spoke, and hub portions, a second similar half of a core plate, means of uniting said plates, detachable hub members carried in the hub portions of the plates for supporting the hub ends of the cores and determining configuration thereof whereby cores placed in each core plate may be brought together to form a single core.

5. In an apparatus for forming cores, a core plate which forms one half of the core, said core plate having rim, spoke, and hub portions, a second similar half of a core plate, means of uniting said plates, detachable hub members carried in the hub portions of the plates for supporting the hub

ends of the cores and determining configuration thereof whereby cores placed in each core plate may be brought together to form a single core, and openings in said plates for insertion of chaplets therein.

6. In an apparatus for forming cores, a core plate consisting of an angular body having a continuous cutaway portion having a core rim and a centrally located cutaway portion for a core hub.

7. In an apparatus for forming cores, a core plate consisting of an annular body having a continuous cutaway portion for forming a core rim and a centrally located cutaway portion for a core hub, the area between said rim portion and hub portion of the plate being angularly disposed to form tapering spoke core portions.

8. In an apparatus for forming cores, a core plate consisting of an annular body having a continuous cutaway portion for a core rim and a centrally located cutaway portion for a core hub, the area between said rim portion and hub portion of the plate being angularly disposed to form tapering spoke core portions and tapering plate core portions intermediate the spoke core portions.

9. In a core, a core consisting of a rim, spoke and hub portions, supporting arbors therefor consisting of an arbor to each spoke having a semicircular transverse member adjacent the hub and bifurcated portion adjacent the rim, each of said arbors overlap at the head and the rim.

10. In a core, a core consisting of a rim, spoke and hub portions supporting arbors therefor consisting of an arbor to each spoke having a semicircular transverse member adjacent the hub and bifurcated portion adjacent the rim, each of said arbors overlapping at the head and the rim, and apertures on the margins of the core adjacent the rim for the insertion of supporting cores.

11. In a process for making cores, placing green sand in a core plate, adjusting an arbor therein, placing green sand in another core plate, and joining said core plates to one another to unite the faces by placing said plates on ends adjacent to one another and progressively moving the plates toward one another so that when united the plates will be in a vertical position substantially and can be placed in an oven to bake the core, and placing chaplets in position through openings in said plates prior to baking.

12. In a process of making cores, placing green sand on a core plate after having placed in position hub positioning detachable means on said core plate, placing arbors in said sand so that the inner and outer ends thereof will overlap, selecting and filling with green sand a second core plate after having placed a detachable hub

member in position therein, and uniting said plates by joining one edge first and joining the rim of said plates so that the sand surfaces will be adjacent to one another.

- 5 13. In a process of making cores, placing green sand on a core plate after having placed in position hub positioning detachable means on said core plate, placing arbors in said sand so that the inner and
10 outer ends thereof will overlap, selecting and filling with green sand a second core plate after having placed a detachable hub

member in position therein, uniting said plates by joining one edge first and joining the rim of said plates so that the same 15 surfaces will be adjacent to one another, placing said assembled cores and plates in an oven and baking, removing from the oven and removing the plates and inserting supporting members in apertures in the periphery of said cores.

In testimony whereof, I affix my signature.

GEORGE WALTHER.
